UNITED STATES PATENT OFFICE

MERRITT E. PIXLEY, OF CLACKAMAS COUNTY, OREGON

GUIDE FOR SAW BLADES IN WOOD SAWING

Application filed June 6, 1932. Serial No. 615,481.

My invention relates to the art of cross cut sawing generally in the cutting of logs or sticks of wood into desired lengths, and it consists mainly in a woodsman's implement for guiding and for supporting a saw in its operative reciprocatory cutting motion across a log, for instance.

By the aid of my device the weight of a saw is mechanically supported and the saw operated, it may be, by one person only, and it may be applied for use below the log or stock to be cut, in a method commonly denominated undercutting by sawyers. The utility of my invention consists mainly in its applicability as an undercutter, although it may be also used, not without advantage, in sawing stock from above as well as from below.

What constitutes my invention will be hereinafter described in detail and succinctly defined in the appended claims.

In the accompanying drawing which illustrates my invention in that form of embodiment at present preferred.

Figure I is a side elevation of my implement fixed as in use on a log and supporting below the log a saw in the undercutting operation.

Figure II is a side elevation of my implement detached, showing in full lines the saw supporting arm thereof adjusted on one side of its supporting post and showing in dotted lines the said arm adjusted in reversed position on the post.

Figure III is a side elevation of my implement having its movable parts folded together as for transportation.

Referring to the numerals on the drawing, 1 indicates a supporting post, which is preferably of skeleton shape, constructed of two parallel side strips 2 of metal, for instance wrought iron, which are unified by a series of cross-overs 3, that are spaced apart at suitable frequent intervals and which are preferably wrought into integral union with the strips 2 to complete the post.

The outer faces of each of the strips 2 are substantially smooth save for the provision upon each of them of a graduated series of transverse grooves 4.

My implement in its entirety is of conveniently portable weight, so that an operator may easily carry it about with him in the woods or wherever the stock to be cut is located.

The post 1 is provided at one end with a preferably integral cross-head 5 which terminates at one end in a longitudinally tapered blade 6 that is preferably, in effect, a point of a spatula-shape as illustrated, and which at the other end is provided with a driving head 7 which enables an operator, as by impact upon it of a hammer, to drive the blade 6 for use longitudinally into a log, for instance, with cleavage effect at any point of disposition therein he may select. The flat shape of the blade 6 holds it in use against torsional strain, and anchors the implement in the fixed position required for use.

Upon the post 1 is provided a thereunto snug fitting, sliding, preferably rectangular metallic collar 8 that is adapted at will to be slipped by manipulation from end to end of the post 1, or to any intermediate position thereon.

The collar 8 is made of heavier metal on one side to provide support 9 for a saw-supporting spring arm 10. The said arm is preferably provided next the post 1 with a foot 11 and is pivotally secured to the support 9 at its upper side as by a pin bolt 12. A heel 13 on the foot 9 affords positive means for supporting the arm 10 in the horizontal position when the foot 11 is attached to the support 9, and the collar 8 fixed to the post.

To the bottom of the support 9 on the collar 8 is fixed, as by tap bolts 14, a strong spring support 15 having a sharp free edge 16 that is adapted to engage any one of the grooves 4 and to support the foot 11 and the arm 10 thereon in any one of a series of adjustments determined by the one of the series of grooves 4 that may be selected for interengagement with the sharp edge of the support 15.

The free end of the arm 10 is provided with a co-axial bearing pin 17 upon which is pivotally secured a guide drum 18 whose

periphery is provided with an annular groove or series of grooves 19 in one of which the back of a saw 20 runs. The resiliency of the arm 10, aided by that of the spring 5 support 15, serves to press the saw, working in one of the grooves 19, with operative cutting effect, against the stock which it is designed to cut.

- Upon the end of the post 1, opposite that 10 end which carries the head 5, is provided a reduced end 21 that constitutes a coaxial extension of the post and affords means for turning the collar 8 when it is slipped upon the end 21 of the post, as it may be at will. 15 The end 21 is preferably cylindrical in shape and carries a nut 22 that is threaded to the outer extremity of the reduced end 21, and which serves to prevent accidental separation of collar 8 from the post. 20 A set screw 23, operable as by a handle 24, is preferably provided for securely fixing, by its impingement against either of the strips 2, the collar 8 in any position in relation to the groove 4 for engagement with 25 which the edge 16 of the support 15 may be adjusted.

The operation of my device will, it is believed, be understood by one skilled in the art, in view of the foregoing, without further description.

What I claim is:

1. A saw guide which consists of the combination with a supporting post and means for anchoring it at one end to the stock to be cut, of a collar adjustable upon the post, a resilient arm pivotally secured to the collar, and means for effecting graduated adjustment of the collar on the post.
2. In a drag saw guide the combination 40 with a post and a sliding collar thereon, of a resilient arm pivotally carried on the collar, a spring support on the collar having a sharp edge adapted to engage any one of a series of transverse grooves provided on the post.
3. In a drag saw guide the combination 45 with a post and a sliding collar thereon, of a resilient arm pivotally carried on the collar, a spring support on the collar having a sharp edge adapted to engage any one of a series of transverse grooves provided on the post, and means for securely fixing the collar to the post in any position to which the collar may be adjusted.
5. In a drag saw guide the combination 50 with a post and a sliding collar thereon, of a resilient arm pivotally carried on the collar, a spring support on the collar having a sharp edge adapted to engage any one of a series of transverse grooves provided on the post, means for securely fixing the collar to the post in any position to which the collar may be adjusted, and a cross head 60 on the post adapted to be driven into a log 65 for anchoring the post thereto.

5. A saw guide which consists of the combination with a supporting post and means for anchoring it at one end to the stock to be cut, of a collar adjustable upon the post, a resilient arm pivotally secured to the collar, means for effecting graduated adjustment of the collar on the post, and means to permit turning the collar on the post for reversing the position of the resilient arm upon the post.

6. In a drag saw guide the combination with a transversely grooved post, means for anchoring it to a log, and a sliding collar on the post, of a resilient arm, a foot therefor pivoted to the collar, a heel on the post constituting a positive support for the arm, a spring having an edge adapted to engage the individual grooves of the post for the purpose of adjustment, and means for fixing the collar on the post in any position to which it may be adjusted thereon.

In testimony whereof, I have hereunto set my hand.

MERRITT E. PIXLEY.
